UNITED STATES PATENT OFFICE.

EDWARD VASSALLO HARTFORD, OF DEAL, NEW JERSEY.

DESIGN FOR A CASING FOR ELECTRIC STARTERS.

44,369.

Specification for Design.

Patented July 22, 1913.

Application filed May 2, 1913. Serial No. 765,134. Term of patent 7 years.

To all whom it may concern:

Be it known that I, EDWARD VASSALLO HARTFORD, a citizen of the United States, residing at Deal, in the county of Monmouth and State of New Jersey, have invented a new, original, and ornamental Design for a Casing for Electric Starters, of which the following is a specification, reference being had to the accompanying drawing, forming a part thereof.

The said drawing is a front elevation of a casing for electric starters made in accordance with my new design.

I claim—

The ornamental design for a casing for electric starters as shown.

In witness whereof I have hereunto set my hand in the presence of two subscribing witnesses, this 29th day of April, 1913.

EDWARD VASSALLO HARTFORD.
